UNITED STATES PATENT OFFICE.

OLOF F. EDQVIST, OF DENVER, COLORADO.

ROTARY GAS-ENGINE.

1,108,152.

Specification of Letters Patent. Patented Aug. 25, 1914.

Application filed May 13, 1913. Serial No. 767,280.

To all whom it may concern:

Be it known that I, OLOF F. EDQVIST, a subject of the King of Sweden, residing in the city and county of Denver and State of Colorado, have invented a new and useful Rotary Gas-Engine, of which the following is a specification.

This invention relates to improvements in rotary combustion engines.

The object of the invention is to provide an engine of this character, comprising a cylinder or a plurality of cylinders rotatably mounted on a fixed or stationary shaft, said cylinders having pistons and means for so connecting them to the shaft that each of said pistons is given a plurality of cycles or reciprocations, during each complete revolution of its cylinder, whereby explosive mixture is drawn into said cylinders, compressed, exploded, and expelled therefrom, thereby causing said cylinders to revolve upon said shaft, valved ports being provided for admitting explosive mixture to said cylinder, at predetermined times, and for discharging the exploded gases therefrom at predetermined times.

Further, to provide an engine comprising a circular casing rotatably mounted on a stationary shaft having a central crank portion, diametrically opposite pairs of cylinders being supported within said casing, having pistons, rock arms being mounted on said shaft which are connected at their ends to the rods of the adjacent pistons, means being employed for connecting said rock arms and the crank portion of said shaft, means also being provided for admitting explosive mixture to said cylinders at predetermined periods, whereby explosions in the cylinders cause their revolution about the shaft, the connection of the pistons with the crank portion of the shaft causing them to make four cycles or reciprocations during each revolution of the cylinders.

These objects are accomplished by the mechanism illustrated in the accompanying drawings, in which:

Figure 1, is a vertical, longitudinal sectional view of the improved engine. Fig. 2, is a transverse sectional view on the line 2—2 of Fig. 1. Fig. 3, is a similar sectional view on the line 3—3 of Fig. 1. Fig. 4, is an interior view of one half member of the casing detached from the shaft, the cylinders being removed for clearer illustration. Fig. 5, is an exterior view of Fig. 4. Fig. 6,

is a side view of the casing, showing the intake pipes connecting the hollow portion of the shaft with the ports back of the cylinders. Fig. 7, is a side view on a much smaller scale, showing the exhaust pipes which lead from the exhaust port to the muffler. Fig. 8, is a perspective view of a portion of the stationary shaft, showing more clearly the cams for operating the inlet and exhaust valves. Fig. 9, is a front view of one of the double cranks which connect the pairs of rock arms. Fig. 10, is a perspective view of one of the links which connect the double cranks with the crank portion of the shaft. And Fig. 11, is a plan view of the plate for holding the valve casings in place.

Similar letters of reference refer to similar parts throughout the several views.

Referring to the accompanying drawings, the numerals 1 and 1^A designate standards, in which is rigidly mounted a shaft 2, having a central crank portion 3, one end of said shaft having an axial bore or chamber 4, and apertures 5, which extend through the shaft to said chamber, the purpose of said chamber being fully set forth hereinafter.

Upon the shaft 2, is revolvably mounted a circular casing, comprising semi-circular members 6 and 7, which are connected by bolts 8, which pass through transverse ribs 9, which extend across the ends of said members. Spokes 10 and 10^A, which radiate from hubs 11 and 11^A, are secured to opposite sides of the circular casing, and the hubs 11 and 11^A are mounted on the shaft 2, the bores of said hubs being of enough greater diameter than the shaft to provide space for pairs of inner and outer rings 12 and 13 respectively, provided with registering ball

races between which are placed anti-friction balls 14, the rings 13 fitting tightly in the hubs 1, while the rings 12 fit tightly upon the shaft. Upon the hub 11 is rigidly secured a gear wheel 15, which meshes with a pinion 16 on a shaft 17, mounted in a bearing in the adjacent standard 1, the shaft 17 being the power-transmitting shaft, as will be understood. The semi-circular members 6 and 7, which form the circular casing, comprise spaced parallel members, which are not only integrally connected by the ribs 9, but also by integral base blocks 18 and 19, which are diagonally opposite, and whose respective faces are parallel with each other. These bases support cylinders 20 and 21, respectively, the rear ends of which fit into

5 circular recesses formed in said bases; and these cylinders are formed with flanges 22, which are secured to the bases and thus secure the cylinders thereto. Ports 23, extend longitudinally through the bases from one cylinder to the other, and communicating with each of these ports are inlet and exhaust valves 24 and 25 respectively, which are seated in casings 26, which fit into circular recesses in the bases. The valve casings have tubular extensions 27 through and beyond which the valve stems 28 extend, and upon the ends of these stems are screwed nuts 29, between which and the end walls of the valve casings are interposed expansion coil springs 30, which normally hold the valves upon their seats. The valve casings are held in the bases by metal plates 31, having bifurcated ends, as shown in Fig. 11, which straddle the tubular extensions 27, the plates being screwed to the bases. The inlet valve casings have apertures 32, which communicate with inlet ports 33 in the bases, and the exhaust valve casings have apertures 34, which communicate with exhaust ports 35, in the opposite ends of the bases from the inlet ports.

30 The valves 24 and 25 are operated in the following manner: Rock shafts 36 and 37 respectively are pivotally mounted on each of the members 6 and 7 of the circular casing, so that the two shafts on each member are in axial line, and the shafts on one member are diametrically opposite those on the other member. Upon the inner ends of these rock shafts, are secured lever arms 38 and 39 respectively, which normally engage the ends of the valve stems 28. Upon the outer ends of these rock shafts are arms 40 and 41 respectively, which stand at right angles to the lever arms 38 and 39, so that the rock arms with the arms on their inner and outer ends are practically in the nature of bell cranks. To the free ends of the arms 40 and 41 are pivotally secured the outer ends of push rods 42 and 43, the inner ends of which extend through guide apertures in lugs 44, formed on diametrically opposite sides of plates 45, which are secured on the 45 inner ends of the hubs 11 and 11^a of the casing. The inner ends of the push rods 42 and 43 engage arms 46 and 47 respectively, which are pivotally connected at their outer ends to the plates 45. The inner ends of 50 these arms carry anti-friction rollers 48, the arms 46 on the intake side of the casing being in line with a cam 49, on the shaft 2, while the arms 47 on the exhaust side of the casing are in line with a cam 50, on said 55 shaft, as clearly shown by Figs. 1 and 2. Thus, when the arms 46 and 47 are engaged by the cams 49 and 50 respectively, they are thrown outward, carrying with them the push rods 42 and 43, which rock the shafts 60 36 and 37, and the lever arms 38 and 39 are

thereby caused to press upon the ends of the valve stems and lift the valves from their seats, whereby explosive mixture is admitted to the pair of cylinders on one side of the casing, or exploded gases exhausted from the 70 cylinders on the opposite side of the casing, as the case may be.

75 The cylinders 20 and 21 are provided with the usual type of pistons 51 and 52 respectively, to which are pivotally connected piston rods 53 and 54 respectively, which extend slightly beyond the cylinders, and each pair of diametrically opposite rods are connected at their outer ends to rock arms 55, which are pivotally mounted upon the shaft 80 2. By this means the pistons 51 in the cylinders 20, and the pistons 52 in the cylinders 21, are operated in unison, but the pistons on one side are compressing while those on the diametrically opposite side are exhausting, as will be understood. The opposite ends of the rock arms 55 are connected by tie rods 56, so as to hold them in parallel 85 relation.

90 Upon the crank portion 3 of the shaft 2, are pivotally mounted a pair of links 57 and 58, which, for convenience of connection, are each made in halves, which are united by screws as shown in Fig. 10, but when such links are provided with ball bearings, the 95 openings therein would be large enough to permit them to be passed over the shaft and thus allow them to be made in a solid piece. The outer ends of these links are in the form of hubs, the lengths of which are equal to 100 twice the thickness of the links, and these hubs form bearings for the connecting pins of double crank arms 59 and 60 respectively, the free ends of which terminate in pins 61 and 62 respectively, which extend through 105 hubs 63 on the opposing faces of the rock arms 55. The hubs are located adjacent to the ends of the rock arms, and the pins pass through them and are secured by cotter pins 64, or in any other suitable way.

110 The hubs of the links 57 and 58 extend through bearing rings 65 and 66 respectively, which form a part of and project from the connecting members of U-shaped slides 67 and 68, the side members of which 115 are formed with grooves 69, which are V-shaped in cross section. These grooved side members have V-shaped outwardly extending projections 70 at their ends, which lie in correspondingly shaped grooves 71, formed 120 in guide bars 72, which centrally of their length are mounted on the shaft 2, their opposite ends being secured to lugs 73, projecting from the ribs 9, which connect the parallel members of each of the semi-circular sections forming the circular casing. Balls are retained in the grooved sides of the slides, by the V-shaped projections 70, as shown, and these balls bear against the sides 125 of the said grooves, and those in the guide 130

bars 72, and reduce the friction between the slide and slideway to a minimum.

On diametrically opposite sides of the hub 11^A, and in line with the inlet ports 33, are integral enlargements 74, which are formed with threaded apertures, which open into the bore of the hub, and in these apertures are screwed glands or bushings 75, in which are screwed the inner ends of inlet pipes 76, their outer ends being screwed into elbows 77, which are threaded to the inlet apertures 33.

Within the bore of the hub 11^A, are placed rings 78, one of which bears against the circular plate 45, on the inner end of the hub, while the other bears against the ball bearing rings at the other end of the hub. The opposing faces of the rings are stepped, and in the stepped portions are placed ordinary packing rings 79, and against the rings 78 and the packing rings are placed rings or washers 80, which hold the packing rings upon the stepped portions of the rings 78. The rings 78 are held apart by rods 81, which are reduced in diameter at their opposite ends where they pass through the said rings, to form shoulders, which bear against the rings. The washers 80 are loosely mounted on the rods 81, and are held apart by expansion coil springs 82, which surround the rods and bear against the washers. The annular space between the washers 80, communicates with the hollow portion of the shaft 2, through the apertures 5 in said shaft, and with the inlet pipes 76, so that explosive mixture, drawn through the hollow shaft from a carburetor—not shown—passes through the apertures 5, into the annular space between the washers 80, and through the intake pipes and ports, to the cylinders. With this cage form of packing ring, the bore of the hub 11^A is effectively packed on each side of the openings leading to the intake pipes. The packing rings are also held in place, and when worn they can easily and quickly be replaced with new rings.

In Fig. 7, I have shown, on a greatly reduced scale, a side elevation of the exhaust side of the engine. Into the exhaust ports 35 are screwed elbows 83, and similar elbows 84 are screwed into holes in the gear wheel 15, which is rigidly mounted on the hub 11. The elbows 84 are screwed into the inner face of the gear wheel, as shown by dotted lines, and nipples 85 which are connected by unions 86 are screwed into each adjoining pair of elbows 83 and 84, as shown. Against the wheel 15 is placed a muffle 87, which is rigidly mounted on the hub of the adjacent standard 1. This muffle comprises a circular block having an annular channel 88, which registers with the apertures in the gear wheel 15, into which the elbows 84 are screwed. An exhaust pipe 89 is threaded to

an aperture in the muffle, which communicates with the channel 88, and this pipe may lead to any desired point for discharging the exhaust. The outer rim of the muffle is preferably machined and fits tightly against the wheel 15, and its hub portion is also machined and fits tightly against the hub 11 of the engine casing, so that tight joints are maintained at these points, which prevents the escape of the exhausting gases. Spark plugs 90 and 91, are screwed into the base blocks 19 and 20, respectively, midway between the parallel members, which make up the half sections of the casing, and these plugs communicate with the ports 23, in the blocks, back of the cylinders. The plugs are connected by conductor wires 92 and 93 respectively, with metal conductor rings 94 and 95 respectively, which are mounted on an insulating ring 96, which is rigidly secured upon the outer end of the hub 11^A. These conductor rings fit on annular stepped portions upon opposite sides of the insulating ring 96, and are thus separated by an annular collar 97, which is flush with the outer surfaces of the rings 94 and 95. An annularly stepped insulating ring 98 is rigidly secured upon the hub of the standard 1^A, adjacent to the end of the hub 11^A, and at opposite points on the step of this ring are embedded contacts 99 and 100, which are in position to be engaged by a spring contact 101, on the outer end of the hub 11^A. Upon opposite points of the rim of the insulating ring 98, are secured arms 102 and 103 respectively, which carry rollers 104 and 105 respectively, at their outer ends, which bear upon the metal conductor rings 94 and 95. The contacts 99 and 100, are connected by wires 106 and 107 with a source of electric energy, and the roller carrying arms 103 and 104 are also connected with the source of energy by wires 108 and 109, so that at predetermined points in the rotative travel of the cylinders the contact 101 engages one or the other of the contacts 99 and 100, thereby closing a circuit through one of the spark plugs and the source of energy, the current passing through the frame of the engine to one pole of the plug—say the plug 90—thence through the wire 92, to the conductor ring 94, thence through wire 109 to the source of energy, and thence through wire 106 to contact 99, thus completing a circuit, which causes a spark in the port 23, by which the gas in the cylinders 20 is exploded. The wires 106 and 107 pass through apertures in the insulating ring 98, to the contacts 99 and 100, and the conductor wire 92 connected with the plug 90 passes through an aperture in the insulating ring 96, to the conductor ring 94, so as to be out of the way of the arms 102 and 103, when the engine is in operation.

The operation of the improved gas engine

is as follows: Assuming that the parts are in the positions shown in Fig. 2, the pistons of the cylinders 20 are at the limit of their compression strokes, and the pistons of the cylinders 21 are at the limit of the exhaust stroke, and the links 57 and 58 are in direct line. Upon the explosion of the gas in the cylinders 20, impetus is imparted to the rotary casing, and as it turns its guide bars 72 draw upon the slide 67 and push upon the slide 68, which slides are connected respectively to the double cranks 59 and 60, whereby movement is imparted to the rock arms 55, in the direction of the rotation of the casing, but the connection between the rock arm and crank portion of the shaft causes the pistons to move slower than the cylinders, and when the casing has completed a quarter rotation, the parts stand in the position shown in Fig. 3, in which the pistons of the cylinders 20 are at the limit of their explosion strokes, while the pistons in the cylinders 21 are at the limit of their intake strokes. In the position, illustrated in Fig. 2, the slide 67 is at the limit of its outward movement, while the slide 68 is at the limit of its inward movement. As the slide 67 draws the link 57, it is also drawn in by the said link to the position shown in Fig. 3, and while the outer end of the link moves in an arc equal to one fourth of a complete rotation of the casing, and the end of the double crank to which it is attached moves in the same arc, the ends of said crank which are attached to the rock arms move in a much smaller arc, thus retarding the action of the rock arms. While the outer end of the link 57 travels in an arc equal to a fourth of a complete rotation of the casing, the outer end of the link 58 moves only from the position shown in Fig. 2 to that shown in Fig. 3, so that the result of this short movement of the link 58 is precisely the same as that accomplished by the long movement of the link 57. The next quarter turn of the casing causes the pistons to move faster than the cylinders, and as the cylinders swing to the reverse of the position shown in Fig. 2, the mixture in the cylinders 21 is compressed, and at the same time the valve 25 is opened by the engagement of the roller arm 47 with the cam 50, and exploded gas is driven from the cylinders 20. During the next quarter turn of the casing explosions occur in the cylinder 21, while the valve 24 is opened by the engagement of the roller arm 46 with the cam 49, to admit explosive mixture to the cylinders 20. At each quarter rotation of the casing, the parts assume the positions shown respectively in Figs. 2 and 3. The links and the double cranks are of equal length from center to center, by which the required movement or throw of the rock arms is effected.

Having described my invention, what I

claim as new and desire to secure by Letters Patent, is:

1. In a rotary combustion engine, the combination with a stationary shaft having a crank portion, of a casing rotatably mounted on said shaft, cylinders supported in said casing in diametrically opposite pairs, and having pistons and rods connected therewith, rock arms rotatably mounted on the shaft and connecting the diametrically opposite piston rods in pairs, links on the crank portion of the shaft, cranks connected to the free ends of said links and to the rock arms intermediate of their connection with the shaft and with the piston rods, inlet and exhaust valves for said cylinders, and cams for operating said valves at predetermined points in the rotative travel of the casing.

2. In a rotary combustion engine, the combination with a stationary shaft having a crank, a casing rotatable on said shaft, cylinders supported in said casing in diametrically opposite pairs, and having pistons and piston rods, rock arms rotatable on the shaft and connecting the diametrically opposite piston rods in pairs, cranks pivotally connecting said rock arms on opposite sides of the shaft, links connecting said cranks and the crank portion of the shaft, of means for turning the links on their axes, as the casing is rotated, whereby the pistons are caused to reciprocate, inlet and exhaust valves connected with said cylinders, and cams for operating said valves at predetermined points in the rotative travel of the casing.

3. In a rotary combustion engine, the combination with a stationary shaft, a casing rotatably mounted thereon, having diametrically opposite integral base members, each provided with pairs of cylinder-receiving sockets, and ports connecting said sockets, of cylinders in said sockets, having pistons and rods, inlet and exhaust valves in said bases communicating with said ports and with inlet and exhaust ports also formed in said bases, means for operating said valves at predetermined points in the rotative travel of the casing, rock arms rotatable on the shaft which connect diametrically opposite piston rods in pairs, and means connected with the rock arms and with the shaft for imparting a rocking movement to said arms and thereby causing the pistons to reciprocate during the rotation of the cylinder.

4. In a rotary combustion engine, the combination with a stationary shaft having a crank portion, of a casing rotatably mounted on said shaft, cylinders supported in said casing in diametrically opposite pairs, and having pistons and rods, and rock arms rotatable on said shaft and connected at their ends to diametrically opposite piston rods, of double cranks pivotally

connecting said rock arms on opposite sides of their centers, and links connecting said double cranks and the crank portion of the shaft, said arms being thereby rocked whereby the pistons are each given four reciprocations during each rotation of the casing.

5. In a rotary combustion engine, a stationary shaft having a crank portion, a casing rotatably mounted thereon having diametrically opposite pairs of cylinders, with pistons and rods, rock arms rotatable on said shaft and connected with diametrically opposite piston rods, double cranks connecting the rock arms on opposite sides of their centers, links connecting the double cranks and the crank portion of the shaft, guides extending across the casing, and slides connected to said links and mounted on said guides, whereby when the casing rotates 10 the links are turned and the double cranks operate the rock arms so that the pistons are each given the intake, compression, explosion, and exhaust strokes, during one complete rotation of the casing.

25 6. In a rotary combustion engine, a stationary shaft having a crank portion, a casing rotatable thereon having oppositely positioned cylinders, with pistons and rods, rock arms on said shaft connecting opposite piston rods in pairs, double cranks connecting the rock arms on opposite sides of the shaft, links connecting the double cranks and the crank portion of the shaft, parallel guides mounted on the shaft and connected 30 to opposite points of the casing, slides mounted in said guides and having eyed members which are connected to said links whereby when the casing is rotated 35 the links are turned upon the crank, and the double cranks operate the rock arms to cause four reciprocations of each piston during each rotation of the casing.

7. In a rotary gas engine, the combination of a stationary crank shaft having one crank pin, and a casing rotatably mounted on said shaft, adjacent to said crank, a pair of cylinders on each side of said crank pin, the cylinders of each pair of cylinders being arranged on opposite sides of said crank 45 shaft and within said casing, a piston provided with an oscillating piston rod in each cylinder, a pair of rock arms mounted on said shaft and connected together to oscillate in unison with each other, and means 50 connected with said walking beams and including a slideway mechanism arranged and adapted to permit said pairs of cylinders and pistons to rotate around said stationary crank shaft in operative four cycle order. 55

8. In a rotary combustion engine, a stationary shaft having a crank portion, a casing rotatably mounted thereon, cylinders arranged in diametrically opposite pairs, in said casing, and having pistons, and rods 60 connected therewith, rock arms on said shaft connecting diametrically opposite pairs of piston rods, cranks connecting the outer portions of said rock arms on each side of the shaft, links connecting said cranks with 65 the crank portion of the shaft, said links and cranks being of equal length from bearing center to bearing center, valves for admitting explosive mixture to said cylinders and for exhausting exploded gases 70 therefrom, cams on said shaft for operating said valves, spark plugs in operative connection with said cylinders, and a sparking system connected with said plugs and operable by the rotation of the cylinders. 75

In testimony whereof I affix my signature in presence of two witnesses.

OLOF F. EDQVIST.
